VEHICLE DOOR SURFACE PROTECTING SHIELD

Norman Edward Tedder, Tulsa, Okla.

Application October 16, 1950, Serial No. 190,300

2 Claims. (Cl. 16-1)

1

This invention relates to so-called automotive accessories and attachments and has more particular reference to a novel and improved shield which is expressly designed and adapted to cover and protect a vulnerable surface on an automobile or other vehicle door, whereby to prevent the surface from becoming defaced.

It is a matter of common knowledge that a door surface in close proximity to the exterior door handle is often accidentally marred by scratches. That is to say, it is not unusual to trace scratches to finger rings. Often when one catches hold of the door handle to operate it, a ring on the finger may strike and scar the highly polished surface between the handle and door. Then, too, loose keys on key rings also account for minor scars. It is therefore the object of the instant invention to provide a simple, practical and ornamental shield which may be readily applied and thus interposed between the handle and the stated vulnerable door surface, said shield functioning as a protector for the surface.

Another object of the invention is to provide a suitably constructed shield in which manufacturers, users and others will find their expected needs fully met, contained and successfully available.

More specifically, the invention has to do with an ornate shield which is neat, unusually simple in construction, and which may be applied by merely boring a hole in the door to accommodate a retaining clip carried by the reverse side of the shield.

Other objects and advantages will become more readily apparent from the following description and the accompanying illustrative drawings.

In the accompanying sheet of drawings, wherein like numerals are employed to designate like parts throughout the views:

Figure 1 is a side elevational view showing the exterior side of an automobile or equivalent vehicle door showing the handle and also showing the improved shield, the manner in which it is constructed and applied.

Figure 2 is a view similar to Figure 1 with the shield appearing in dotted lines and showing the keeper hole which is formed in the door to accommodate the stated clip.

Figure 3 is a central vertical section on the plane of the line 3—3 of Figure 1, looking in the direction of the arrows.

Figure 4 is a horizontal section on the line 4—4 of Figure 3, looking in the direction of the arrows.

2

Referring now to the drawings by numerals and lead lines, the automobile door, which is conventional, is denoted by the numeral 6 and the conventional handle means by the numeral 8. The handle operates the usual latch (not shown) and includes a hand grip 10 for opening and closing the door, which hand grip is, as a general rule, substantially in spaced parallelism in relation to the painted surface 12 of the door.

The shield is denoted by the numeral 14 and, of course, may be made from any suitable sheet material. Although commercial plastics might well be employed in constructing the shield, metal is preferably employed. Therefore, it may be said that, broadly speaking, the shield is a metal plate. In practice, the exterior or obverse surface of the plate 16 is highly finished with chromium plating. Also, the plate is bent and otherwise fashioned so that it will conform intimately with the contours of the surface 12 with which it intimately coacts. Therefore, when the plate is applied it is in direct metal-to-metal contact with the surface 12. Further, the plate is of an area or size so that it will underlie and accommodate the sweep of the hand grip 10. Assuming that the hand grip 10 is normally in a horizontal plane, the upper portion of the plate projects above the handle and the lower portion projects below the handle, as shown to advantage in Figure 1. The projecting lower portion need not be necessarily wide and, by preference, is formed with a gradually narrowing and ornamental appendage 18. Marginally, the plate is of a predetermined outline or configuration whereby it is thus both ornate and appealing in appearance. The marginal edges 20 are turned to form a smoothly contoured, circumscribing flange. This prevents the presence of undesirable sharp edges. The upper edge portion, the widest part, is formed with a lateral adapter lip 22, as best shown in Figure 3. Also as here shown, the lip projects underneath and preferably between the usual door bead 24 and the surface of the door. This constitutes one retaining device for the shield. The other device is in the form of a resilient metal U-shaped retainer clip 26 which, as best shown in Figure 4, has its bight portion welded or otherwise secured to the reverse side of the appendage 18 and which has substantially V-shaped opposed fingers 28—28 to releasably engage in a keeper hole 30 provided in the door panel 32. It will be necessary, in practice, to bore a hole in the panel 32 to provide the stated keeper hole, this as is obvious. By thus providing retaining means at the top and also at the

bottom portion, the shield will be effectively applied and satisfactorily retained in place.

With the shield interposed between the hand grip and surface 12 of the door 6 and located in proper relationship in respect to the swingable hand grip 10, the aforementioned vulnerable surface will be aptly shielded and guarded with the result that said surface will be protected against marring at all times.

It is to be mentioned that the shield may also be utilized as an ornament and may be engraved with a crest, insignia, or monogram.

The pattern, size and bent contour will vary to meet the requirements of automobile door surfaces of varying forms.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. In combination, a vehicle door having a strip of molding affixed to the exterior surface of the door, a latch operating exterior handle located in general spaced parallelism to said exterior surface, said door having a keeper hole spaced downwardly from said molding, and a readily attachable rigid surface covering and protecting shield superimposed directly against said surface, said shield being independent of but situated between the handle and said surface to prevent the hand of the user of the handle from

rubbing and marring the surface when actuating said handle, said shield conforming to the surface contours immediately contacted thereby and having its obverse surface exteriorly chromium plated, said shield being provided at its upper end with a lateral adapter and retaining lip interposed between said molding and the adjacent portion of said exterior surface and having its lower end provided with resilient detents projecting into said keeper hole, whereby said shield is interlocked with said door.

2. As a new article of manufacture, an escutcheon-like shield for covering and protecting a given surface of a vehicle door within the vicinity of the usual handle of said door, said shield being in the form of a rigid plate having its marginal edges laterally bent to make direct contact with and conform to the contours of said door, the obverse side of said plate being non-corrosive and scratch-resistant, spring prong means secured to the reverse side of said shield and projecting laterally therefrom and adapted to be anchored in a keeper hole provided therefor in said door, and the upper marginal edge having a retention lip coextensive with the width of the plate and adapted to interlock with the existing moulding on said door, whereby said shield is independent of and solely supported by way of said door.

30 NORMAN EDWARD TEDDER.
